Primary Examiner—Mitchell I Siegel

(74) *Attorney, Agent, or Firm*—Oliff & Berridge, PLC

(57) **CLAIM**

The ornamental design for a golf club head, as shown and described.

DESCRIPTION

FIG. 1 is a front elevational view of a golf club head embodying the inventive design.

FIG. 2 is a top plan view thereof.

FIG. 3 is a toe-side elevational view thereof.

FIG. 4 is a heel-side elevational view thereof.

FIG. 5 is a rear bottom perspective view thereof.

FIG. 6 is a rear elevational view thereof.

FIG. 7 is a heel-side front perspective view thereof.

FIG. 8 is a bottom plan view thereof.

FIG. 9 is a toe-side front perspective view thereof.

FIG. 10 is a toe-side bottom perspective view thereof; and,

FIG. 11 is a heel-side bottom perspective view thereof.

The dash-dot chain lines immediately adjacent the shaded areas represent the bounds of the claimed design, while all other broken lines are directed to environment and are for illustrative purposes only; the dash-dot chain lines and other broken lines form no part of the claimed design.
